(57) **CLAIM**

The ornamental design for a vehicle ceiling panel, as shown and described.

DESCRIPTION

FIG. 1 is a front view of a vehicle ceiling panel showing our new design;

FIG. 2 is a rear view thereof;

FIG. 3 is a right side view thereof;

FIG. 4 is a left side view thereof;

FIG. 5 is a top (plan) view thereof;

FIG. 6 is a bottom view thereof;

FIG. 7 is an elevated front-left perspective view thereof;

FIG. 8 is an elevated rear-right perspective view thereof; and,

FIG. 9 is a sectional view of line 9—9 of FIG. 5.

The shading (i.e., dark and light coloring) shown all over the surface of the present ceiling panel in each of the Figures (except for an end view of line 9—9) indicates the shape of the three-dimensional surface of the present design.
